UNITED STATES PATENT OFFICE.

GEORGE BECKER, OF NEW YORK, N. Y.

COAT-SHIRT.

No. 925,269.

Specification of Letters Patent. Patented June 15, 1909.

Application filed December 28, 1908. Serial No. 469,567.

To all whom it may concern:

Be it known that I, GEORGE BECKER, a citizen of the United States, residing in the borough of Manhattan, city, county, and 5 State of New York, have invented certain new and useful Improvements in Coat-Shirts, of which the following is a specification.

My improvements relate to the class of 10 men's shirts known as coat shirts, closed at the back and opening and closing at the front for the entire length of the garment.

The object of the invention is to afford a 15 garment which provides adequately for the comfort and convenience of the wearer, particularly when worn in connection with a low cut vest, as in full dress; and the invention consists in the construction and arrangement of parts herein described and claimed 20 specifically.

In the accompanying drawings, Figure 1, 25 is a view of my improved coat shirt spread open; Fig. 2, a view of the same with the skirt closed and the bosom flaps open; Fig. 3, a partial view similar to Fig. 2, showing a different adjustment of waist band; Fig. 4, a front view of my improved coat shirt closed; Fig. 5, is a section upon an enlarged 30 scale taken upon plane of line 5—5—Fig. 4; Fig. 6, is a section upon an enlarged scale taken upon plane of line 6—6—Fig. 4.

The body A, of the shirt is of the usual coat form opening and closing at front for the full length of the garment. The bosom 35 flaps b, b, are attached only to the collar band c, the yoke y, and the reinforced side strips r, r. These flaps b, b, at their junction with the extensions of the said side strips r, r, which constitute the waist bands w, w, 40 are firmly secured to said side strips r, r by "button hole" stitching d, as an additional means of reinforcing them against the strain to which they may be subjected at these points. The bosom flaps b, b, extend below 45 the stitching d, from which points they are free and unattached, except to each other when secured by the usual bosom studs, buttons or the like. In other words they are not attached to the front laps a, a, of the 50 skirt of the garment A, but are free to slide over the same and adapt themselves to the form and position of the wearer whether standing or sitting, without crumpling or buckling up. Furthermore the absence of 55 stitching across the lower portions of the bosom is a great advantage in dress shirts,

adding materially to their appearance,—visible stitching being objectionable, and tending also to create a line of deflection or bending when the bosom flaps b, b, are sewed 60 to the skirt flaps, a, a, as heretofore.

The waist bands w, w, are formed with button holes and provided with buttons, or equivalent means of attachment, and are formed so as to over-lap each other more or 65 less, to suit the convenience and comfort of the wearer. Thus in Fig. 2, they are shown as secured together so as to over-lap each other to the full extent, whereas in Fig. 3, the over-lap is less and the waist bands 70 w, w, are thus better adapted to the comfort and convenience of a pot-bellied person. Obviously this adjustment of the waist bands w, w, may be effected by any plurality 75 of fastening devices, as for instance hooks and eyes, and I do not restrict my invention in this respect.

By thus constructing my improved coat shirt I obviate the discomfort and inconvenience attendant upon the use of stiff bosoms, since the lower portions of the bosom flaps are free to adapt themselves to all requirements of use without danger of buckling or distortion. I furthermore avoid undue and objectionable strain on the parts, 80 and stitching, and thereby increase the life and length of wear of the garment. By making the waist bands adjustable to the size and shape of the wearer, I also add materially to the convenience and comfort of the 85 latter. By my construction I produce an ideal dress shirt.

What I claim as my invention and desire to secure by Letters Patent, is,

1. In a shirt of the character designated, 95 the combination with the body of the garment comprising a collar band, yoke and reinforcing strips, of bosom flaps attached only to said collar band, yoke, and reinforced strips, said bosom flaps extending 100 downward below such reinforced side strips, and being free of the front skirt laps, said front skirt laps of the garment being formed with waist bands formed of extensions of said side strips and provided with a plurality 105 of fastening devices, whereby the width of the over-lap may be varied, for the purpose described.

2. As an improved article of manufacture, 110 a coat shirt comprising a body, a collar, a yoke, reinforced side strips, and bosom flaps secured to said neck, yoke and a major por-

tion of the side strips, said reinforced side strips being extended beyond the lowermost point of connection with the bosom flaps and forming waistbands, said waistbands being provided with detachable fastening means, said bosom flaps being constructed to overlap and having their lower portions free of the front skirt lap of the shirt,

whereby they adapt themselves to all requirements of use without buckling or distortion.

GEORGE BECKER.
